UNITED STATES PATENT OFFICE.

HARRY E. KAY, OF EAST TEMPLETON, MASSACHUSETTS.

TURBINE-MOTOR.

No. 913,731.

Specification of Letters Patent.

Patented March 2, 1909.

Application filed May 25, 1908. Serial No. 434,720.

To all whom it may concern:

Be it known that I, HARRY E. KAY, a citizen of the United States, residing at East Templeton, in the county of Worcester and 5 State of Massachusetts, have invented a new and useful Turbine-Motor, of which the following is a specification.

This invention relates to a motor which, while capable of operation by means of 10 other sources of power, is especially designed as a water motor.

The principal objects of the invention are to provide for getting a much higher efficiency from a source of power than has been 15 done heretofore with turbine wheels. In order to accomplish this result, two series of wheels are employed, arranged alternately and facing in opposite directions, so that the water discharged from one wheel will enter 20 the next one at such an angle that it will act upon it with full force. A number of these wheels are arranged in such a way that those facing in one direction rotate a shaft, and those facing in the other direction rotate a 25 second shaft the other way. Means is provided whereby the shafts and wheels are conveniently located to receive and transmit a maximum amount of power.

Further objects and advantages of the invention will appear hereinafter.

Reference is to be had to the accompanying drawing, in which—

Figure 1 is a longitudinal central sectional view of a water motor constructed according 35 to this invention, Fig. 2 is a similar view on an enlarged scale showing a detail, and Fig. 3 is a fragmentary elevation of a detail.

The device is shown as comprising a casing 10 having an in-take 11. The in-take 40 discharges into a chamber 13 which is connected by a longitudinal cylindrical passage 14 with the outlet 15. The passage may conveniently be horizontal as shown. The casing is provided with two bearings 16 and 45 17 at opposite ends thereof and preferably in axial alinement. In these bearings are arranged shafts 18 and 19. Each of these shafts is supported outside the casing by independent bearings 20, and each carries a 50 pulley 21 or other device by which power may be transmitted from them. Two sets of turbine wheels 22 and 23 are employed facing in opposite directions, and are arranged alternately. All the wheels 22 are 55 fixed to the shaft 18 while the wheels 23 have openings 24 therethrough through

which the shaft 18 passes freely. Arranged outside of all the wheels is a cylindrical casing 25 fixed to the wheels 23, and in which the wheels 22 freely rotate. The last wheel 60 23 which is fixed to the casing 25 is also fixed to a hub 26 secured to the end of the shaft 19. As the shafts 18 and 19 rotate in opposite directions the hub 26 is extended to form a bearing for the end of the shaft 65 18 and the two shafts are spaced apart a short distance to form a chamber 27 in which an anti-friction ball-bearing 28 is placed.

I am aware that two turbine wheels have 70 heretofore been placed to rotate in opposite directions, and connected up with the driving mechanism in various ways, but by means of this invention the number of driving wheels can be increased indefinitely so that 75 such number may be employed as is found most efficient for the head or the other conditions which may be present in each case. It will be understood, of course, that the addition of pairs of wheels will increase the 80 efficiency up to a certain point and beyond that the use of more wheels will practically not give further increase in power.

The operation of the device will readily be understood, the water entering the wheel 85 22 at the left turns it in the direction of the arrow, and is discharged in such a direction that it will have its greatest efficiency to turn the next wheel 23 in the other direction so that the shaft 18 and casing 25 will rotate 90 95 oppositely. The water discharged from the first wheel 23 will enter the wheel 22 so as efficiently to operate it. A number of wheels should be chosen so that the water discharged from the last one will have practically no velocity, the entire head having been employed in the course of the passage of the water through the casing to rotate the several wheels therein. It will be seen also that the shafts 18 and 19 and the casing 25 100 105 are arranged in a very practicable manner on account of the locations and arrangement of the bearing, and of the passage 14 and other features of construction. For the purpose of lubricating the anti-friction bearings 28 and also the bearings of the wheels which are not fixed to the shaft 18, both of the shafts 18 and 19 are preferably provided with longitudinal passages 30 and 31. These passages terminate in the chamber 27 110 and the passage 31 is supplied with a lubricant by means of any ordinary device 32 for

containing the same. This is preferably connected on the end of the shaft 19, as indicated in Fig. 3. The shaft 18 is also provided with passages 33 by which the lubricant can pass to the bearings of the wheels 23. Thus these bearings, as well as the anti-friction bearings are thoroughly lubricated from a readily accessible point.

While I have illustrated and described a preferred embodiment of the invention and a certain number of pairs of turbine wheels, and while I have illustrated the invention as employed for operation by a head of water, I am aware that the invention may be carried out in many other ways, and that many modifications may be made without departing from the scope thereof as expressed in the claims. Therefore, I do not wish to be limited to all the details and features shown and described, but

What I do claim is:—

1. In a multiple turbine motor, the combination of a fixed casing having an in-take, an outlet, and a horizontal passage connecting said in-take with the outlet, said casing also having bearings beyond the opposite ends of said passage, a pair of horizontal shafts in longitudinal alinement extending into the casing from opposite ends, a series of turbine wheels in the passage, all facing in the same direction, a second series of turbine wheels in the passage, all facing in the other direction, and located and arranged to rotate independently of the first series of wheels, and a rotary casing in said passage surrounding all of said wheels and fixed to the second set thereof, one set of wheels being fixed to one of the shafts, and the rotary casing to the other.

40 2. In a turbine motor, the combination of a plurality of turbine wheels arranged axially in alinement, each alternate wheel facing oppositely from the others, a shaft passing through said wheels to which all the wheels facing in one direction are fixed, a casing surrounding the wheels to which all the remainder of the wheels are fixed, a second shaft in line with the first shaft and secured to said casing, anti-friction bearings between the ends of said shafts, and means for directing a stream through all of said wheels in succession inside the casing, whereby the shafts will be rotated in opposite directions.

55 3. In a turbine motor, the combination of two shafts arranged end to end, a hub fixed to the end of one shaft and projecting over the end of the other and forming a bearing therefor, anti-friction bearings in said hub between the shafts, means for supporting the opposite ends of the shafts, and two series

of turbine wheels one fixed to one shaft and the other connected with the other.

4. In a water motor, the combination of a casing having an in-take, a chamber at the 65 end of the in-take, an outlet, and a horizontal passage connecting said chamber with the outlet, said casing also having two bearings in alinement beyond the ends of said passage, a pair of shafts each extending into 70 the said casing through one of said bearings, independent bearings outside the casing for supporting said shafts, a series of turbine wheels all facing in the same direction and fixed on one of said shafts, a second series of 75 turbine wheels all facing in the other direction and located to rotate independently of the shaft on which the other wheels are fixed, and a casing surrounding all of said wheels and fixed to the second set thereof, 80 said casing being secured to the shaft to which the first set of wheels are not fixed.

5. In a turbine motor, the combination of two shafts arranged end to end, a hub fixed to the end of one shaft and projecting over 85 the end of the other and forming a bearing therefor, anti-friction bearings in said hub between the shafts, means for supporting the opposite ends of the shafts, two series of turbine wheels one fixed to one shaft and the 90 other connected with the other, said shafts having passage therethrough extending to said anti-friction bearings.

6. In a motor, the combination of two shafts arranged end to end, turbine wheels 95 for turning said shafts in opposite directions, an anti-friction bearing between the ends of the shafts, a hub on one shaft forming a bearing for the end of the other and providing a casing for said bearing, said shafts having longitudinal passages, and means for supplying a lubricant through one of said passages to the anti-friction bearing and to the other shaft.

7. In a motor, the combination of two 105 shafts arranged end to end, turbine wheels for turning said shafts in opposite directions, a bearing between the ends of the shafts, a hub on one shaft forming a bearing for the end of the other and providing a casing for 110 said bearing, said shafts having longitudinal passages, and means for supplying a lubricant through one of said passages to the bearing and to the other shaft.

In testimony whereof I have hereunto set 115 my hand, in the presence of two subscribing witnesses.

HARRY E. KAY.
